UNITED STATES PATENT OFFICE.

CHARLES J. KLEIN, OF MILWAUKEE, WISCONSIN. ASSIGNOR TO THE CUTLER-HAMMER MFG. CO., OF MILWAUKEE, WISCONSIN, A CORPORATION OF WISCONSIN.

DESIGN FOR AN ATTACHMENT-PLUG CAP.

57,841.

Specification for Design.

Patented May 10, 1921.

Application filed March 23, 1917. Serial No. 157,021. Term of patent 14 years.

To all whom it may concern:

Be it known that I, CHARLES J. KLEIN, a citizen of the United States, residing at Milwaukee, in the county of Milwaukee and State of Wisconsin, have invented a new, original, and ornamental Design for an Attachment-Plug Cap, of which the following is a specification, reference being had to the accompanying drawing, forming part thereof.

I claim:

The ornamental design for an attachment plug cap, as shown.

CHARLES J. KLEIN.
